UNITED STATES PATENT OFFICE

WILLIAM GINTELL, OF NEW YORK, N. Y.

COAT CONSTRUCTION

Application filed April 13, 1929. Serial No. 354,914.

This invention relates to new and useful improvements in coat constructions, especially to overcoats for boys, and aims to provide an improved construction in the body and sleeves of the coat whereby to enable the parents of the boy owning said coat to quickly lengthen the body portion, as well as the sleeves thereof.

In carrying out the present invention, the coat material in the body and sleeves is considerably longer than the normal length of the sleeves and coat when the same is placed upon the market. This is also true of the lining in the coat body and sleeves, and this extra length of coat material and lining is when the coat is manufactured folded inwardly, and the abutting edges of the coat material and lining are interconnected by a chain stitch or the like in order to enable the coat material and lining to be pulled apart, so that the extra length of the lining and coat material can be let out, and then again stitched for an obvious increase in the length of the coat body and sleeves thereof.

I have determined by actual experiment that a coat constructed in accordance with this invention may be manufactured and marketed at a cost no greater than the cost of the coats now upon the market, and even though in some instances, there may be a slight additional expense, this is entirely offset by reason of the fact that when the coat becomes too short for the owner thereof, it can be inexpensively and easily lengthened to enable its being used for several years, which is not now possible in the coats upon the market, as it is frequently necessary to discard the garment after it has been outgrown while in a wearable condition.

In the drawing wherein like reference characters indicate corresponding parts throughout the various views:—

Figure 1 is a side elevation of a boy's coat constructed in accordance with the present invention, the lower end of the body portion thereof at one side being partially upturned and the lower end of the sleeve illustrated, being partially broken away.

Figure 2 is an enlarged fragmentary longitudinal section through the lower end of the

coat sleeve, illustrated and taken substantially upon the line 2—2 of Figure 1.

Figure 3 is a similar view taken through the lower end of the coat body substantially upon the line 3—3 of said Figure 1, and

Figure 4 is a view disclosing in full lines the normal construction of the lower end of either the coat body or one of the sleeves, the dotted lines representing the manner in which the lining and coat material may be arranged to increase the length of either the coat body or sleeves thereof.

Now having particular reference to the drawing, A designates generally a boy's coat constructed in accordance with the present invention, while B indicates one of the sleeves thereof. The general features of construction of this coat are the same as the structural features of similar coats now upon the market. The present improvement resides in the provision of constructing the garment in such a manner as to readily enable the length of the coat body as well as the sleeves thereof to be increased, and this in such a manner as not to detract from the appearance of the coat between the body and sleeve lining and the coat material.

In carrying out the present invention, the material forming the body of the coat is designated by the reference character 5, while the body lining is designated 6. The length of the body material 5 is such as to permit a coat of normal length to be produced, while at the same time allowing the lower edge of the coat material to be turned inwardly upon itself and then downwardly to provide at the lower edge of the coat an outer, inner and intermediate material ply 7, 8 and 9.

Similarly, the length of the lining is such as to enable the lower edge thereof to be turned inwardly and then downwardly providing an outer, inner and intermediate ply 10, 11 and 12. The inward turning of the coat material and lining is such as to bring the edges of the fold lines of the plies 9 and 9 of the coat material and the plies 10 and 11 of the lining into engagement, after which said fold lines are interconnected by stitching 13, the nature of which is such as to enable it to be pulled out without difficulty

whereupon the innermost plies of the coat material and lining may be let out, and again stitched for the obvious purpose of increasing the length of the garment.

5 This increased length from the original construction of the coat as per the full lines in Figure 4 being illustrated by the dotted lines in the same figure.

10 The same manner of constructing the coat sleeves at the outer ends thereof is identical with the manner of constructing the lower edge of the coat body, as clearly illustrated in Figure 3 and the description set out previously herein, with reference to the body of 15 the coat, will suffice for the sleeve construction.

20 In view of the foregoing description when considered in conjunction with the accompanying drawing, it will be apparent that I 25 have provided a novel, simple and serviceable coat construction wherein the length of the coat body as well as the sleeves may be increased by unskilled workers, and even though I have herein shown and described the invention as consisting of a certain manner or method of construction, it is nevertheless to be understood that some changes may be made therein, without affecting the spirit and scope of the appended claim.

30 Having thus described my invention, what I claim as new, and desire to secure by Letters-Patent, is:

35 In a coat construction wherein the material forming the coat body and sleeves as well as the linings thereof are of a length greater than the normal length of the coat or sleeves and linings therefor, said extra lengths being turned inwardly and then downwardly to provide two extra plies of 40 the coat material and lining inwardly of the material and lining, the folds of the lining being disposed above and on the same general plane as the folds of the coat material and a row of stitching between the meeting 45 fold lines of the extra plies of coat material and lining, all in a manner and for the purpose described.

In testimony whereof I affix my signature.

WILLIAM GINTELL.
